J. T. BUNN.
WATER HEATING DEVICE FOR GAS STOVES.
APPLICATION FILED SEPT. 10, 1915.
1,182,345.

Patented May 9, 1916.

UNITED STATES PATENT OFFICE.

JOSEPH TURNER BUNN, OF WASHINGTON, DISTRICT OF COLUMBIA.

WATER-HEATING DEVICE FOR GAS-STOVES.

1,182,345.

Specification of Letters Patent.

Patented May 9, 1916.

Application filed September 10, 1915. Serial No. 50,053.

To all whom it may concern:

Be it known that I, JOSEPH T. BUNN, a citizen of the United States of America, residing at Washington, in the District of Columbia, have invented certain new and useful Improvements in Water-Heating Devices for Gas-Stoves, of which the following is a specification, reference being had therein to the accompanying drawing.

10 This invention relates to a water heating device for gas stoves and the like, and has for its object the production of a simple and efficient heating mechanism which may be applied to the ordinary gas stove without necessitating the changing of the construction of that portion of the stove which is placed above the burner.

20 Another object of this invention is the production of a simple and efficient supporting means for attaching the water heating device to a stove.

25 With these and other objects in view this invention consists of certain novel combinations, constructions, and arrangements of parts as will be hereinafter fully described and claimed.

30 In the accompanying drawing, Figure 1 is a perspective view, on an enlarged scale with respect to the other figures of the drawing, showing the manner of supporting the water heating tubes upon a stove. Fig. 2 is a central longitudinal section through the device. Fig. 3 is an enlarged longitudinal section through a portion of one of the connecting tubes, showing one of the connecting joints in cross section. Fig. 4 is a side elevation of one of the supporting brackets for the heating tubes. Fig. 5 is a section taken on the line 5—5 of Fig. 4. Fig. 6 is a top 35 plan view of an embodiment of the invention, showing the transversely connected heating tubes connected to a series of T-joints. Fig. 7 is a plan view of an embodiment of the invention showing the heating 40 pipes connected in series. Fig. 8 is a detail perspective view of a cover adapted to be placed over the heating tubes when so desired for the purpose of retaining the heat around the heating tubes.

45 By referring to the drawing it will be seen that the stove is provided with the usual side rails 1, which side rails are provided with ledge portions 2 upon their inner faces, and are also provided with the projecting 50 flanges 3.

A plurality of brackets 4 are adapted to engage the flanges 3, and these brackets 4 comprise a pair of similarly constructed sections, each section having a pair of spaced jaws 5 for fitting over the flanges 3 and supporting the brackets 4 in a suspended position upon the side rails 1. The respective sections of the brackets 4 are connected by means of a link member 6, which link member is adjustably connected to the sections of the brackets 4 by means of bolts or pins 7 passing through the adjusting apertures 8 formed in the connecting link 6. The respective sections of the brackets 4 are provided with inturned flanges 9, which inturned flanges 9 constitute rests or supports for the heating tubes adapted to be supported thereon.

In the preferred embodiment, as illustrated in Fig. 1, a pair of communicating pipes 10 are employed, which communicating pipes are provided with a plurality of spaced collars 11 for the purpose of receiving the oppositely threaded ends of the heating pipes 12. These heating pipes 12 are 50 preferably formed of thin metal and have enlarged ends 13 which are externally threaded, as clearly illustrated in Fig. 3 of the drawing, the respective ends being oppositely threaded, as above stated, for the 55 purpose of permitting the heating pipes 12 to be conveniently threaded into the respective collars 11 formed upon the communicating pipes 10. By carefully considering the drawing it will be seen that the enlarged 60 portion 13 of the heating pipes 12 will present a smooth surface upon the outer end thereof for permitting a wrench to conveniently grip the pipes for the purpose of 65 threading the pipes 12 into the collars 11. 90

The communicating pipes 10 are provided with inturned elbow portions 14, which are connected by end pipes 15, and these end pipes 15 are similarly constructed to the pipes 12 and are adapted to rest upon supporting flanges 9 upon the respective sections of the brackets 4, thereby constituting an efficient means for supporting the heating device upon the stove.

A plurality of integral ears 16 are carried 105 by the communicating pipes 10 and are arranged in spaced relation and preferably in alignment with the collars 11. These ears 16 are adapted to rest upon the ledge portion 2 and also act as a supporting means for the 110

communicating pipes 10 throughout their entire length.

A supply pipe 17 of suitable construction may be connected in any desired manner to 5 one of the communicating pipes 10 and a discharge pipe 18 may also be connected to the opposite end of one of the communicating pipes 10 to constitute a return pipe, and this pipe 18 is adapted to extend back under 10 the pipes 12, as illustrated in dotted lines in Fig. 1, and may then be brought in any desired manner to the source of water supply, or reservoir, preferably passing parallel with the pipe 17.

15 Bolts 19 pass through the flanges 9 of the brackets 4, and these bolts 19 are adapted to pass down through the bottom of the stove for permitting the anchoring of the brackets 4 in engagement with the stove, in any 20 suitable or desired manner.

As illustrated clearly in Figs. 1 and 2 the heating pipes 12 are provided with a plurality of spaced integral beaded portions 20 formed thereon to constitute ledges upon 25 which a receptacle or pan may be seated thereby elevating the receptacle or pan above the level of the pipes 12. It will, therefore, be seen by this that the beaded portions 20 will constitute supporting legs for spacing 30 the receptacle placed upon the pipes away from the upper face of the pipes, as illustrated in dotted lines in Fig. 2 of the drawings.

In Fig. 6 there is shown an embodiment 35 of the invention wherein the transverse heating pipes 12' may be connected to individual T-joints 10', which joints 10' are in turn connected by means of a union joint 21. The T-joints 10' are, of course, provided with the integrally projecting tongues 16' similar to the tongues 16 illustrated in Fig. 1.

In the embodiment disclosed in Figs. 1, 2, and 3, it will be seen that the heating pipes 45 12 are arranged in parallel or multiple relation. In the embodiment shown in Fig. 7 the heating pipes 22 are arranged in series, the respective pipes being connected by means of the connecting elbows 23. It, of 50 course, should be understood that the elbows 23 are provided with supporting tongues 24 similar to the tongues 16, for supporting the elbows 23 in engagement with the side rails 1 of the stove. The pipes 22, like the pipes 55 12, are provided with beaded portions or collars 25 arranged in spaced relation thereon for the purpose of constituting supporting legs for a pan placed upon the heating pipes 22. It, of course, should be understood that the water supply may be taken 60 to and from the pipes 22 in any desired

manner, such for instance, in the same manner as that described with reference to Fig. 1.

In Fig. 8 there is shown a pan, which is 65 used in connection with the present invention, comprising a rectangular body which is adapted to be inverted over the heating pipes 12 and 22 for retaining the heat around these pipes. The pan 26 may be provided 70 with an aperture 27 to allow the heat to pass out therethrough and into engagement with a pan or receptacle placed upon the pan 26 when the same is in an inverted position.

What is claimed is:

1. A water heating device of the class described, comprising a plurality of communicating pipes, transverse heating pipes connected to said communicating pipes, means for supplying water to and from said communicating pipes, said communicating pipes provided with a plurality of projecting tongues, said tongues adapted to engage the side rails of a stove for supporting said communicating pipes throughout their entire length, a plurality of adjustable brackets supported upon said side rails and adapted to engage the respective ends of said heating device for constituting a support therefor, said brackets provided with a plurality of spaced jaws adapted to firmly grip the side rails of a stove and firmly hold said brackets in engagement therewith.

2. In combination with a plurality of supporting brackets a plurality of heating 95 pipes, said supporting brackets comprising a pair of adjustable sections, each section provided with an inwardly extending flange, means carried by said sections for supporting the same in engagement with a stove, and an adjustable link connecting the respective adjacent ends of said sections.

3. A water heating device of the class described comprising a plurality of communicating pipes, transversely extending heating 105 pipes connected to said communicating pipes, means for supplying water to and from said communicating pipes, means carried by said communicating pipes and projecting laterally therefrom and adapted to overhang a support for suspending said pipes, said transversely extending pipes provided with integral beads formed intermediate the ends thereof and constituting means for supporting a receptacle above the outer face of said transversely extending pipes, and means extending under the respective ends of said heating device for constituting a support for the ends thereof.

In testimony whereof I hereunto affix my 120 signature.

JOSEPH TURNER BUNN.
